HIGH-VOLTAGE BUSHING

Harvey M. Owren, Oakland, Calif., assignor to the United States of America as represented by the United States Atomic Energy Commission

Application January 2, 1952, Serial No. 264,447

1 Claim. (Cl. 174—18)

1

The present invention relates to an improved high voltage bushing for use in connection with the isolation of large alternating or direct current voltages encountered in connection with electrical equipment, such as transformers.

In the use of very high voltages of the order of hundreds of kilovolts it is commonly necessary to employ bushings having a length of ten feet or more in order to prevent electrical breakdown, and elements of this size while quite practicable outdoors are often too large for indoor installations having even nominal space limitations. Additionally, bushings are conventionally designed and built for use with alternating current voltages or alternatively for direct current voltages and certain criteria governing bushing design makes a bushing designed for one use generally unsuited for another.

The present invention is adapted for use with alternating or direct current voltage isolation and further may be made considerably smaller than conventional bushings designed for comparable voltages. These advantages are obtained by the provision of a combination of insulations particularly adapted for alternating current voltage and for direct current voltage, by the elongation of the voltage creep path and by expansion of the areas having potential differences therebetween.

Accordingly, it is an object of the present invention to provide an improved high voltage bushing.

It is another object of the present invention to provide a high voltage bushing having expanded surfaces between which an impressed potential exists.

It is another object of the present invention to provide an improved high voltage bushing having means making substantially uniform the potential gradient across the insulation thereof.

It is a further object of the present invention to provide an improved high voltage bushing having in combination a corona shield and liquid and solid insulation.

It is a still further object of the present invention to provide an improved high voltage bushing having a corona shield immersed in insulating fluid.

Numerous other advantages and possible objects of the invention will become apparent to those skilled in the art from the following description taken together with the attached drawings, wherein:

Figure 1 is a longitudinal sectional view of a

preferred embodiment of the invention taken on a horizontal line through the center of Figure 2;

Fig. 2 is a sectional view taken at line 2—2 of Fig. 1; and

Fig. 3 is a schematic wiring diagram of a possible application of the invention.

Considering the invention in general, it will be seen to comprise a bushing 12 having central electrical conductor 11 extending through an insulating envelope 12 which engages same in sealed relation and contains an insulating fluid 13. Mounting means 14 about the exterior of envelope 12 extends interior thereto and is expanded along conductor 11 as shown. Additional insulation is provided about conductor 11 and numerous other elements are provided to complete an operable bushing assembly as set forth below.

Considering now the invention in more detail both as to elements and functions thereof, and referring to Figs. 1 and 2, there is shown an insulating envelope 12 which may include a plurality of stacked insulating cylinders 16, 17, and 18 which are formed of porcelain or the like and which are disposed concentrically about metallic tubular conductor 11. A pair of discs 19 and 20 are disposed about conductor 11 with one adjacent each end thereof and engaging adjacent insulating cylinders 16 and 18 to define an enclosed chamber which is filled with an insulating fluid 13, such as transformer oil. Bottom disc 20 is preferably formed of insulating material while top disc 19 may be made of metal or the like. A bottom retainer ring 22 is fastened about conductor 11 below insulating disc 20 to hold same in position and a gasket disposed therebetween seals the connection about conductor 11. A top retainer ring 23 is disposed about conductor 11 near the top thereof and a hold-down nut 24 is threaded onto conductor 11 to force top ring 23 against disc 19 and to seal the connection about conductor 11 by forcing top ring 23 against appropriate gasket means inserted in said connection. There may also be provided a terminal cup 26 secured atop insulating disc 19 by top retainer ring 23 to contain appropriate terminal means.

With regard to the central portion of insulating envelope 12, it will be noted that the illustrated embodiment of the invention includes a third disc 27 about conductor 11 formed of insulating material and employed to join insulating cylinders 16 and 17. The use of two insulating cylinders 16 and 17 and insulating disc 27 therebetween instead of a single insulating cyl-

inder is advantageous when the total length of insulation is great, in that the cost and difficulty of manufacture is decreased, and also is necessary when the insulating material is of laminar form in that it has been found that very high voltages tend to discharge along the laminations. Also, disposed somewhat centrally of the bushing assembly is mounting means 14 which is preferably discoidal and formed of metal or the like. Mounting means 14 is disposed about the exterior of insulating envelope 12 and also extends 5 interiorly thereof between insulating cylinders 17 and 18 in sealing relation thereto. Apertures may be provided through mounting disc 14 spaced about same exterior to insulating envelope for engagement with attachment means, such as 10 bolts, by which the bushing assembly may be mounted upon electrical equipment or the like.

Internal to insulating envelope 12 there is disposed a corona shield 28 which is formed as a cylinder of somewhat lesser diameter than insulating envelope 12 and has the edges thereof rolled outwardly. The flaring or rolling of the ends or edges of shield 28 preferably includes a complete turn of the edge as may be accomplished 20 by joining a bar or tube formed as an anchor ring 29 about each end of shield 28, as illustrated. Corona shield 28 is secured either directly or by intermediate electrically conducting support means to mounting means 14 with shield 25 28 preferably being electrically contacted about the entire circumference at a distance from the ends thereof.

In addition to the above-noted elements there are provided liquid and solid dielectrics internal 30 to insulating envelope 12 and about central electric conductor 11. The solid dielectric is formed as one or more tubes 31 of insulating material, such as Lucite, disposed concentrically about conductor 11 and maintained in position by spacer 35 rings 32 disposed between tubes 31 and between tubes 31 and conductor 11, as shown. Insulating tubes 31 extend along conductor 11 from insulating disc 20 to a point above mounting means 14 that is substantially equal to the distance between insulating disc 20 and mounting means 40 14, and tubes 31 are disposed between shield 28 and conductor 11, preferably closer to conductor 11. The fluid dielectric 13 substantially fills the interior of insulating envelope 12 about conductor 11 and apertures in mounting means 14 and in spacer rings 32 provide communication to all parts of the interior of insulating envelope 12 for filling same with fluid 13.

With regard to relative dimensions of the elements of the bushing assembly, it is to be noted that the application for which the bushing is designed is at least in part determinative of certain of the relationships. In many applications the bottom portion of the bushing will be disposed in a medium having a different dielectric constant than the medium about the upper portion and the ratio of the dielectric constants may be used approximately as the ratio of the distance from the top of the bushing to mounting means 14 to the distance from the bottom of the bushing to mounting means 14. Thus where the bushing is to be mounted partially within equipment including a transformer oil bath and insulating cylinder 18 is to be disposed in oil and cylinders 16 and 17 are to be disposed in air the ratio of the length of cylinder 18 to the combined lengths of cylinders 16 and 17 may be one-half, which is the ratio of the dielectric constants of air and transformer oil. Also the 55 70 75

disposition of corona shield 28 is dependent at least in part upon the same criteria and in the above example corona shield 28 is connected to mounting means 14 with substantially two-thirds of the shield above mounting means 14 and one-third below. It will be appreciated that the above-noted dielectric ratio is important with relation to surface discharge on the insulators and it is presupposed that the insulators are of adequate size to withstand breakdown therethrough with the voltage to be employed.

With regard to the disposition of corona shield 28 and the fluid and solid insulation 13 and 31, respectively, it is to be noted that corona shield 28 in effect expands the area or surface of mounting means 14 internal to the insulating envelope 12. Ordinarily mounting means 14 is maintained at ground potential as by attachment to a transformer tank or the like, and whatever the connection, a potential exists between electrical conductor 11 and mounting means 14. This potential is maintained by insulating fluid 13 and by solid insulation 31, and corona shield 28 is preferably separated from central conductor 11 by a sufficient distance to dispose an adequate amount of insulating fluid 13 therebetween to hold the entire voltage for which the bushing is designed. In addition, solid insulation 31 between corona shield 28 and conductor 11 is preferably provided in sufficient thickness to withstand the entire voltage ratio of the bushing and this has been determined in the case of Lucite to be about one quarter of an inch per 100 kilovolts. By the above provisions the bushing is capable of carrying alternating current voltages or direct current voltages and the possibility of the establishment of a voltage creep path directly between shield 28 and conductor 11 by the alignment of impurities in the insulating fluid is prevented. Direct current voltages can only align the impurities in the insulating fluid from corona shield 28 to insulating tube 31 so that the voltage creep path must then extend along the insulating tube 31 to the end thereof and thus the creep path is made greater than the direct voltage path.

Equal potential lines extend between corona shield 28 and conductor 11 parallel thereto but at the ends of corona shield 28 they curve back toward mounting means 14 and if they are too close together where they intersect the surfaces of insulating cylinders 17 and 18 the potential gradient will be sufficient to cause local discharge which may then spread to produce electrical breakdown across the insulator surface. With sharp edges at the ends of corona shield 28 the equipotential lines will curve sharply back toward mounting means 14 and will become bunched together to produce regions of large potential gradient; however, the present invention obviates this difficulty by providing curved edges on corona shield 28 whereby the equipotential lines follow wide curves having an even greater separation than they do in the region between conductor 11 and mounting means 14. The potential gradients across all parts of insulating cylinders 17 and 18 are thus minimized and made more uniform to prevent discharge thereacross.

Considering now a typical application of the invention, reference is made to Fig. 3 wherein there is shown in elevation a bushing constructed in accordance with the present invention and mounted upon the tank 41 of a high voltage transformer 42 shown schematically in section. Bolts or the like engage mounting means 14 and

transformer tank 41 to hold bushing 10 in place and lower insulating cylinder 18 is thus disposed within tank 41. The transformer primary winding 43 is connected to an external power supply (not shown) and the secondary windings 44 are connected by leads 45 through the conducting tube 11 of bushing 10 to the exterior of tank 41 where they may be attached to a terminal block or the like. Preferably tubular bushing conductor 11 is sealed at the lower end thereof about 10 secondary transformer leads 45 and the transformer windings 43 and 44 may be disposed in an insulating fluid 46, such as transformer oil. There may be further provided within tank 41 a primary winding shield electrically connected to the primary winding and a secondary winding shield electrically connected to the central tubular conductor 11 of bushing 10. In common practice transformer tank 41 is electrically grounded and thus mounting means 14 and connected corona shield 28 (Fig. 1) are grounded while the central conductor 11 of bushing 10 is maintained at the high voltage of secondary transformer winding 44. By the above-noted construction of bushing 10, electrical breakdown is prevented in bushing 10 whether direct current voltage pulses or alternating current voltages are passed by transformer 42.

While the present invention has been disclosed with respect to a single preferred embodiment, it will be apparent to those skilled in the art that numerous modifications and variations are possible within the spirit and scope of the invention and thus it is not intended to limit the invention except by the terms of the following claim.

What is claimed is:

A high voltage bushing for use with electrical equipment disposed in a tank containing insulating fluid comprising, a sealed insulating cylinder, an insulating fluid within said cylin-
